(57) **CLAIM**

The ornamental design for the flash card set, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front side view of the first flash card of a Flash Card Set showing my new design.

FIG. 2 is a front side view of the second flash card thereof;

FIG. 3 is a front side view of the third flash card thereof;

FIG. 4 is a front side view of the fourth flash card thereof;

FIG. 5 is a front side view of the fifth flash card thereof;

FIG. 6 is a front side view of the sixth flash card thereof;

FIG. 7 is a front side view of the seventh flash card thereof;

FIG. 8 is a front side view of the eighth flash card thereof;

FIG. 9 is a front side view of the ninth flash card thereof;

FIG. 10 is a front side view of the tenth flash card thereof;

FIG. 11 is a front side view of the eleventh flash card thereof;

FIG. 12 is a front side view of the twelfth flash card thereof;

FIG. 13 is a front side view of the thirteenth flash card thereof;

FIG. 14 is a front side view of the fourteenth flash card thereof;

FIG. 15 is a front side view of the fifteenth flash card thereof;

FIG. 16 is a front side view of the sixteenth flash card thereof;

FIG. 17 is a front side view of the seventeenth flash card thereof;

FIG. 18 is a front side view of the eighteenth flash card thereof;

FIG. 19 is a front side view of the nineteenth flash card thereof; and,

FIG. 20 is a front side view of the flash card set showing my new design in a combined state.

The surface is flat and of no substantial thickness.

(Continued)

The broken lines depict the bounds of the claimed design and form no part of the claimed design.
